UNITED STATES PATENT OFFICE.

WILLIAM A. TORREY, OF MONTCLAIR, NEW JERSEY.

VULCANIZED FABRIC FROM GUMS AND RAMIE AND SIMILAR FIBERS.

SPECIFICATION forming part of Letters Patent No. 354,993, dated December 28, 1886.

Application filed April 5, 1886. Serial No. 197,855. (No specimens.)

To all whom it may concern:

Be it known that I, WILLIAM A. TORREY, of Montclair, in the county of Essex and State of New Jersey, have invented a new and useful Improvement in the Manufacture of Articles Made by the Application of India-Rubber, Gutta - Percha, and other Vulcanizable Gums to Ramie or Similar Textile Fabrics, such as belting, hose, clothing, and the like; and I do hereby declare that the following is a full and exact description thereof.

Belting, packing, hose, clothing, and like articles have heretofore been manufactured by the application of compounds prepared for vulcanization upon cloth or fabric made of cotton, flax, linen, or silk.

The nature of my invention consists in applying india - rubber, gutta - percha, or any other vulcanizable gums to cloths or fabrics made of ramie, rhea, pita, or other cactus plants.

It is but recently that cloth has been manufactured from ramie, and the result has proved that articles manufactured from this fiber have a tensile strength equal at least to six times that of cotton, flax, or hemp. Goods made from ramie are not liable to mildew or rot and will not stretch, thus adding to their value over

any goods made as heretofore of cotton, flax, or hemp.

The application of india-rubber, gutta-percha, or other vulcanizable gums to the goods or fabrics made of rhea (or ramie) is precisely similar to that employed in applying these gums to cotton, flax, or hemp fabrics, and is well known to those skilled in the art.

What I claim as my invention, and desire to secure by Letters Patent, is—

1. The application of india-rubber, gutta-percha, and other vulcanizable gums to goods or fabrics made of rhea, (or ramie,) pita, or other cactus plants, as and for the purpose set forth.

2. The combination of india-rubber, gutta-percha, or any vulcanizable gums with rhea, (or ramie,) pita, or other cactus plants, for the purpose and in the manner described.

3. The improved vulcanized goods and fabrics composed of ramie, pita, or cactus, textile fiber, and a vulcanizable gum, substantially as set forth.

WILLIAM A. TORREY.
